SURFACE GRINDER ATTACHMENT FOR
MILLING MACHINES

Arthur P. Drediske, Rockford, Ill.

Application May 25, 1945, Serial No. 595,672

5 Claims. (Cl. 51—241)

1

This invention relates to milling machine attachments and is more particularly concerned with new and improved grinder attachments readily applicable to the conventional horizontal bar of such machines, whereby to widen the range of usefulness thereof by permitting surface grinding, tool grinding and the like on these machines.

I am aware that grinder attachments have been proposed heretofore for milling machines, but most of them have been objectionable for one reason or another and have therefore not been used to any appreciable extent. It is, therefore, the principal object of my invention to provide a more practical and serviceable attachment, which, by reason of its simplicity and compactness of construction, may be produced at reasonably low cost and which, because of the novel way in which it is constructed and applied to the overarm of the machine and the way in which the motor drive is transmitted to the driven spindle provides a wide range of adjustability and adaptability for different jobs and assures the desired rigidity and relative freedom from vibration so that close accuracy of operation, as required in surface grinding and tool grinding, is obtained.

The invention is illustrated in the accompanying drawing in which

Figs. 1 and 2 are a side view and front view respectively of a milling machine showing a grinder attachment made in accordance with my invention applied thereto, and

Figs. 3 and 4 are sections on the correspondingly numbered lines of Fig. 1 on an enlarged scale.

The same reference numerals are applied to corresponding parts throughout the views.

It will, of course, be understood at the outset that the attachments, with which my invention is concerned, are intended to be sold at relatively low prices as compared with the cost of conventional surface grinders, for application to existing milling machines. There is a real demand for such attachments in many places and particularly in small machine shops, where occasional surface and tool grinding jobs might otherwise necessitate taking that work to some larger shop equipped with a surface grinder. It is the aim of my invention to provide a grinder attachment for milling machines giving substantially the same facility of operation, range of adaptability to different jobs, and close accuracy as a regular surface grinder, at a small fraction of the cost of such a machine.

In the grinder attachment, shown at 6' in Figs. 55 are in spaced relation and have their adjoining

2

1 and 2, the motor 22' is mounted on a shelf 28' that is free to turn about a vertical axis with the bearing 18' relative to a bracket 36 adjustably supported on a bearing 37, which, in turn, is adjustably clamped on the overarm or bar 7' of the milling machine, whereby to permit rotary adjustment of the grinding wheel 20' in a horizontal plane and accordingly greatly increase the range of usefulness of the grinder attachment. 5 The bracket 36 has a pair of parallel guide rods 38 suitably secured thereto, as indicated at 39, and extending therefrom at right angles to the axis of the vertical shaft 40 received in the bracket 36 and forming the axle for rotary adjustment of the bearing 18' and motor 22'. The rods 38 are slidably received in parallel holes 41 provided in the upper portion of the bearing 37, and have V-grooves 42 provided in the outer sides thereof, which slidably receive V-shaped gibs 43 10 that are adjustably mounted in longitudinal grooves 44 provided therefor in the bearing 37 in one side of the holes 41. One of these gibs 42 has a number of screws 45 bearing against the back thereof and adjustably threaded in holes in the bearing 37, so as to take up excess clearance between the rod 38 and the hole 41 for a close working fit of the rod in the hole, regardless of such wear as may occur. The other gib 43 has screws 46 cooperating therewith in a similar way, but 15 these screws have hand levers 47 attached thereto, so as to permit clamping the rod tightly in an adjusted position. Adjustment of the rods 38 inwardly or outwardly is obtained by the turning of pinions 48, which are provided on a cross-shaft 49 and mesh in rack teeth 50 provided on the tops of the rods 38. A bevel gear 51 provided on one end of the cross-shaft 49 has a bevel gear 52 meshing therewith and carried on the end of a shaft 53, that is mounted in the top of the bearing 37 and is arranged to be turned by means of a hand wheel 54 provided on the outer end thereof. Thus, when the screws 46 are loosened, in or out adjustment of the rods 38 may be made to secure the proper positioning of the grinding wheel 20', after which the screws 46 may be tightened again, and in that way the attachment is rigidly secured in adjusted position.

The rotary adjustment of the wheel 20' about the shaft 40 is permitted when the screw 55, 40 which cooperates with a pair of clamping gibs 56 and 57, is loosened by means of its hand lever 58. The gibs 56 and 57 are slideable in a bore 59 in the bracket 36 that is substantially tangent to the vertical bore 60 in said bracket, and the gibs

ends beveled off, as indicated at 61, on the radius of the bore 60, so that when the screw 55 is tightened, these beveled ends exert a clamping action on the periphery of the vertical shaft 40 sufficient to fasten the bearing 18' and motor 22' quite rigidly in an adjusted relationship to the bracket 36. The lower end of the shaft 40 is pinned, as indicated at 62, to the bearing 18', and there are two thin washer-like nuts 63 threaded on the upper end portion of the shaft 40 above the bracket 36 to prevent downward displacement of the shaft 40 in the bracket, the lower one of these nuts being adjusted to take up end play in the shaft 40 and the upper nut, when tightened, serving to lock the lower nut. The reduced upper end portion 64 of the shaft 40 is received in the socket 65 provided therefor in the bottom of the shelf 28', and a set screw 66 threads in the wall of the socket 65 and serves when tightened against the reduced upper end portion 64 of the shaft to clamp the shelf 28' in vertically adjusted relationship to the shaft, thereby permitting take-up of slack in the belts 25' that interconnect the pulleys 23' on the armature shaft of the motor with the pulleys 26' provided on the driven spindle carrying the grinding wheel 20'. The guard 27' for the belts 25' is suitably detachably secured to the attachment.

The bearing 37 is arranged to be clamped in adjusted position on the bar 7' by the tightening of a pair of bolts 67, which are entered in the projecting lugs 68 provided on the split sleeve 69 that is entered in a bore 70 in one end of the bearing 37 in concentric relation to the bore 71 provided in the main body portion of the bearing, in which the bar 7 is received. A split sleeve 72 of crescent-shaped cross-section, whose outer periphery is concentric with and fits snugly within the bore of the sleeve 69 and whose bore is concentric with the bore 71, closely surrounds the bar 7' and serves to clamp the bearing 37 in adjusted position when the screws 67 are tightened. The sleeve 69 being a separate and distinct part from the bearing 37, any distortion of the sleeve, therefore, will not result in transmitting such distortion to the bearing 37. This avoids any likelihood of interference with the easy working of the rods 38 in the holes 41. The lower rear portion of the bearing 37 is of course split, as indicated at 73, to permit extension of the lugs 68 downwardly from the bearing 37, so that access may be had to the screws 67 when the bearing 37 is to be clamped or loosened.

The motor 22' and its supporting shelf 28' will approximately counterbalance the weight of the rest of the attachment with respect to the bar 7' so that the attachment will operate satisfactorily and with minimum vibration in all positions of rotary adjustment relative to the bar. Although pulleys 23' of the same size as pulleys 26' are shown for a one-to-one drive to the wheel 20', it will be obvious that I may provide larger pulleys at 23' for a step-up in speed of operation of the wheel.

The operation of this attachment is believed to be clear from the foregoing description. The wheel 20' is adapted to do many kinds of surface grinding and tool grinding work, and I may, of course, mount other tools on the spindle 19 to perform other operations besides grinding. In the feed movement of the table 11', the work is fed longitudinally with respect to the saddle 10', and in the transverse feed movement of the latter on the vertically adjustable knee 9' the work is adjusted accordingly with respect to the wheel 20'.

20', so as to present all portions of the surfaces to be ground. The fact that the motor 22' is in balanced relation to the rest of the attachment and all of the weight of the attachment is borne by the heavy bar 7' minimizes the likelihood of vibration. The usefulness of the attachment for the grinding of tools is indicated in Figs. 1 and 2, wherein I have shown a tool T mounted between centers 74 on the table 11' preparatory to the grinding thereof in the back and forth feed movements of the table 11'.

It is believed the foregoing description conveys a good understanding of the objects and advantages of my invention. The appended claims have been drawn to cover all legitimate modifications and adaptations.

I claim:

1. An attachment for milling machines comprising an upright bracket of elongated form having a clamp intermediate its ends on a horizontal axis for support adjustably on the horizontal overarm of a milling machine, a substantially horizontal spindle rotatably mounted in one end portion of said bracket and adapted to carry a tool, such as a grinding wheel, on one projecting end thereof, an electric motor for driving said spindle mounted on the other end of said bracket in substantially diametrically opposed counterbalancing relation to said spindle, said motor having an armature shaft, a drive connection between the armature shaft of said motor and the other end of said spindle, a pair of spaced parallel rods slidably mounted in holes provided therefor in said clamp in radially spaced parallel relation to said overarm, said rods being attached at their outer ends to said bracket for adjustably supporting said bracket relative to the clamp and overarm, racks on said rods, a cross-shaft mounted in said clamp carrying pinions meshing with said racks, and manually operable means for turning said cross-shaft.

2. An attachment for milling machines comprising an upright bracket of elongated form having a clamp intermediate its ends on a horizontal axis for support adjustably on the horizontal overarm of a milling machine, a substantially horizontal spindle rotatably mounted in one end portion of said bracket and adapted to carry a tool, such as a grinding wheel, on one projecting end thereof, an electric motor for driving said spindle mounted on the other end of said bracket in substantially diametrically opposed counterbalancing relation to said spindle, said motor having an armature shaft, a drive connection between the armature shaft of said motor and the other end of said spindle, a pair of spaced parallel rods slidably mounted in holes provided therefor in said clamp in radially spaced parallel relation to said overarm, said rods being attached at their outer ends to said bracket for adjustably supporting said bracket relative to the clamp and overarm, racks on said rods, a cross-shaft mounted in said clamp carrying pinions meshing with said racks, and manually operable means for turning said cross-shaft comprising a bevel gear on one end of said shaft, a bevel pinion meshing with said gear, and a shaft attached to said bevel pinion and mounted in the clamp and extending therefrom and having manually operable means carried on the outer end thereof for turning the same.

3. An attachment for milling machines comprising an upright bracket of elongated form having a clamp intermediate its ends on a hori-

zontal axis for support adjustably on the horizontal overarm of a milling machine, a substantially horizontal spindle rotatably mounted in one end portion of said bracket and adapted to carry a tool, such as a grinding wheel, on one projecting end thereof, an electric motor for driving said spindle mounted on the other end of said bracket in substantially diametrically opposed counterbalancing relation to said spindle, said motor having an armature shaft, a drive connection between the armature shaft of said motor and the other end of said spindle, a pair of spaced parallel rods slidably mounted in holes provided therefor in said clamp in radially spaced parallel relation to said overarm, said rods being attached at their outer ends to said bracket for adjustably supporting said bracket relative to the clamp and overarm, racks on said rods, a cross-shaft mounted in said clamp carrying pinions meshing with said racks, manually operable means for turning said cross-shaft, gibs of V-shaped cross-section extending lengthwise in the holes in said clamp and slidably received in V-shaped grooves provided in said rods extending lengthwise thereof, and adjustable screw means threaded in the clamp to adjust the gibs radially relative to the grooves in said rods and to clamp said rods in adjusted position relative to said clamp by means of said gibs.

4. An attachment for milling machines comprising an upright bracket of elongated form having a clamp intermediate its ends on a horizontal axis for support adjustably on the horizontal overarm of a milling machine, a substantially horizontal spindle rotatably mounted in one end portion of said bracket and adapted to carry a tool, such as a grinding wheel, on one projecting end thereof, an electric motor for driving said spindle mounted on the other end of said bracket in substantially diametrically opposed counterbalancing relation to said spindle, said motor having an armature shaft, a drive connection between the armature shaft of said motor and the other end of said spindle, a pair of spaced parallel rods slidably mounted in holes provided therefor in said clamp in radially spaced parallel relation to said overarm, said rods being attached at their outer ends to said bracket for adjustably supporting said bracket relative to the clamp and overarm, gibs of V-shaped cross-section extending lengthwise in the holes in said clamp and slidably received in V-shaped grooves provided in said rods extending lengthwise thereof, and adjustable screw means threaded in the clamp to adjust the gibs radially relative to the grooves in said rods and to clamp said rods in

adjusted position relative to said clamp by means of said gibs.

5. An attachment for milling machines comprising an upright bracket of elongated form having a clamp intermediate its ends on a horizontal axis for support adjustably on the horizontal overarm of a milling machine, a substantially horizontal spindle rotatably mounted in one end portion of said bracket and adapted to carry a tool, such as a grinding wheel, on one projecting end thereof, an electric motor for driving said spindle mounted on the other end of said bracket in substantially diametrically opposed counterbalancing relation to said spindle, said motor having an armature shaft, a drive connection between the armature shaft of said motor and the other end of said spindle, a pair of spaced parallel rods slidably mounted in holes provided therefor in said clamp in radially spaced parallel relation to said overarm, said rods being attached at their outer ends to said bracket for adjustably supporting said bracket relative to the clamp and overarm, an upright shaft rotatable in a bearing provided therefor in said bracket on an axis at right angles to the overarm, a support for the motor fixed on the upper projecting end of said shaft, a support for the horizontal spindle fixed on the lower projecting end of said shaft whereby the horizontal spindle may be rotatably adjusted with the motor relative to the bracket around said shaft as an axis, and means for clamping the shaft in adjustably fixed relation to said bracket.
